United States Patent Office

Des. 200,997
Patented May 4, 1965

200,997

BEVERAGE DISPENSING HEAD OR SIMILAR ARTICLE

James R. Reichow, Edina, Minn., assignor to The Cornelius Company, Anoka, Minn., a corporation of Minnesota

Filed May 26, 1964, Ser. No. 80,152

Term of patent 14 years

(Cl. D2—3)

FIG - 1

FIG. 1 is a front perspective view of a beverage dispensing head, showing my new design.

FIG. 2 is a rear perspective view thereof.

FIG. 3 is an end view thereof.

The dominant features of my design reside in the full lines.

The fragmental showing of a counter top in broken lines is depicted for purposes of illustration only.

I claim:

The ornamental design for a beverage dispensing head or similar article, substantially as shown and described.
